UNITED STATES PATENT OFFICE

152,948

DESIGN FOR A SURFACE TREATING
MACHINE

Francis D. Dolan, Toledo, Ohio, assignor to The
American Floor Surfacing Machine Company,
Toledo, Ohio, a corporation of Ohio

Application October 20, 1948, Serial No. 149,198

Term of patent 14 years

(Cl. D9—2)

To all whom it may concern:

Be it known that I, Francis D. Dolan, a citizen of the United States and resident of Toledo, in the county of Lucas and State of Ohio, have invented a new, original, and ornamental Design for a Surface Treating Machine, of which the following is a specification, reference being had to the accompanying drawing, forming a part thereof.

In the drawing,

Fig. 1 is a side elevational view of a surface treating machine showing my new design; Fig. 2 is a front elevational view thereof; Fig. 3 is a side view opposed to that shown in Fig. 1, and Fig. 4 is a rear end view of the machine.

The dominant features of my design are shown

in full lines. The dotted lines represent a dust bag that is attached to the machine when in use.

I claim:

The ornamental design for a surface treating machine, substantially as shown and described.

FRANCIS D. DOLAN.
